BROOM WINDING MACHINE

Benjamin Koback, 8028 N. Jersey, Portland, Oreg.

Filed Aug. 21, 1957, Ser. No. 679,358

4 Claims. (Cl. 300—14)

The present invention relates to broom winding machines, and more particularly to a machine for winding bristles on the cores of rotary brooms of the type used in street sweepers, polishers, cleaning machines and the like.

The primary object of the invention is to provide automatic means for feeding bristles and tying bristles into the groove of the core in a continuous operation.

A further object of the invention is to lock the bristles in the grooves of the core by rope or cable while delivering the bristles to the core.

Another object of the invention is to provide a trimming device for trimming the ends of the bristles to the proper length simultaneously with the winding of the core.

A still further object of the invention is to provide chains for feeding the bristles into the grooves of the core, the chains having guides thereon for maintaining the bristles in the proper position of alignment while feeding them into the groove. By the use of chains, the position and feeding of the bristles can be accurately controlled while applying them to the grooves of the core and binding them into the grooves.

One of the objects of this invention is to provide a method of feeding the bristles into the spiral grooves formed on the core of the brush wherein the spirals feed the bristle applicator along the core in the applying of the bristles to the core.

A still further object of the invention is to provide an adjustable tension applied to the binding rope through a fair-lead drum having a brake associated therewith.

Other objects and advantages will become apparent in the following specification when considered in the light of the attached drawings, in which:

Figure 1 is a front elevation of the machine illustrating a brush core mounted therein in alignment with the bristle feeding mechanism.

Figure 2 is an end view of the machine shown in Figure 1.

Figure 3 is an enlarged sectional view of the bristle feeding assembly, taken on the line 3—3 of Figure 1, looking in the direction indicated.

Figure 4 is a plan view of the machine with parts broken away for convenience of illustration.

Figure 5 is a fragmentary enlarged sectional view, taken on the line 5—5 of Figure 2, looking in the direction indicated.

Figure 6 is an enlarged fragmentary sectional view, taken on the line 6—6 of Figure 1, looking in the direction indicated.

Figure 7 is an enlarged detail side view of the bristle feeding chains.

Figure 8 is a plan view of a section of chain.

Figure 9 is a sectional view, taken on the line 9—9 of Figure 7, looking in the direction indicated.

Figure 10 is an enlarged fragmentary sectional view, taken on the line 10—10 of Figure 3, looking in the direction indicated.

Figure 11 is a face view of the bristle trimming device.

2

Figure 12 is a plan view of the structure shown in Figure 11.

Figure 13 is a fragmentary sectional view taken on the line 13—13 of Figure 14, looking in the direction indicated.

Figure 14 is a fragmentary side elevation of the brake applying device illustrated in Figure 13.

Figure 15 is an end sectional view, taken on the line 15—15 of Figure 1, looking in the direction indicated.

Figure 16 is a fragmentary enlarged side view of the discharge end of the bristle feeding assembly.

Referring now to the drawings in detail wherein like reference numerals indicate like parts throughout the several figures, the reference character W indicates generally a broom winding machine which includes a frame F.

The frame F has a pair of horizontally disposed channel iron base members 20 running parallel to one another. Vertical disposed posts 21 are fixedly secured to the ends of the base member 20, as by welding or any other suitable means. Vertical posts 22 also are disposed at either end of the base members 20 and extend to a lesser height than the post 21 to the point 23.

Transverse end frame members 24 are fixedly secured to the upper ends of the posts 21 and to extensions 25 disposed at an angle to the vertical at their opposite ends. Upper horizontally disposed frame members 26 and 27 connect the upper ends of the channel legs 21 and 22. The upper frame members 26 and 27 provide rails upon which a carriage C is supported to operate longitudinally of the framework F of the machine W.

Referring particularly to Figure 6, the carriage C includes a platform 28 which rests upon horizontal frames 29. Trunnion wheels 30 are fixedly mounted to a downwardly extending portion 31 of the frames 29 and travel within channel way 32 of the frame members 26 and 27. Fixedly secured to the underside of the horizontal frames 29 is a downwardly extending panel 33, the purpose of which will be more fully described below.

A bristle feeding assembly B is supported by the carriage C and is moved along the upper rails 26 and 27 of the frame F in the operation of the machine W. The bristle assembly B has a flat table 34, referring to Figure 3, which extends from an outer end 35 to the point 36. Extending from the point 36 of the table are side frames 37 which, referring to Figure 10, connect the upper angle bars 38 and the lower angle bars 39 together by welding 40.

The side frames 37 and angle bars 38 and 39 are connected at their inner end at the point 36, by welding. They are spaced apart by a transverse bar 41, which is secured to the lower angle bars 39 by legs 42 welded thereto. It will be noted that the outer ends 43 of the angle bars 38, 39 converge towards one another, referring particularly to Figure 4. The object of which will be later described.

55 The table 34 is supported by hanger bars 44 secured at 45 to the carriage C and to the table 34 at the point 46. The ends 43 of the angle bars 38, 39 are supported by the adjustable hanger rods 47. The hanger rods 47 have threaded tubular members 48 fixedly secured at 49 to the outer ends 43 of the hanger bars 38 and 39.

The upper ends of the hanger bars 47 have threaded tubular members 50 pivotally connected to the carriage C at 51, referring particularly to Figures 1 and 2. Disposed between the threaded tubular members 48 and 50 is a threaded rod 52 having a hand wheel 53 forming part thereof so that the same can be rotated in either direction to raise or lower the outer ends 43 of the bars 38 and 39 in the operation of the machine W.

70 Referring to Figures 3, 4 and 10, endless chains 54 are trained about driving sprockets 55 keyed to a shaft 56 journaled in bearings 57 fixedly mounted to the under-

side of the table 34. The shaft 56 is driven by a motor 58 through a reduction gear box 59 and chain 60. The motor 58 is mounted to a bracket 61, which in turn is supported by the table 34. The opposite end portions of the chains 54 are trained about the idler sprockets 62 journalled on stub shafts 63, the shafts 63 being firmly secured to brackets 64 on the outer ends 43 of the rails 38 and 39.

Referring to Figures 7, 8 and 9, the endless chains 54 have horizontal fingers 65 extending inwardly towards one another. Fingers 66 extend vertically from the chains 54 and form part of the fingers 65. The object of the fingers 65 and 66 is to move the bristles 67 along with the movement of the upper run of the chains 54 to their final destination in a manner to be described later on.

The means of mounting the core 68 within the framework F of the machine W will now be described, referring to Figures 1, 3 and 5. An arbor shaft 69 is journalled within bearings 70 fixedly secured to the vertical posts 22 and 22A. A tail stock 71 is journalled within bearings 72 fixedly secured to the carriage 73. The carriage 73, referring particularly to Figure 15, is supported by trunnion wheels 74 journalled to the base 75 of the carriage 73 and operate within channel ways 76 of the base frame 20. An adjustable brace 77 is fixedly secured to the upper edge of the carriage 73 at 78 and has a trunnion wheel 79 operating within the channel way 76 of the base frame 20 for maintaining the carriage 73 in a vertical position.

The adjustable brace 77 has an adjusting hand wheel 77' for varying the length of the brace 77 for aligning the tail stock 71 with the arbor 69. In the operation of the machine W there is a side strain applied to this assembly, and when this strain is applied it tends to move the tail stock 71 out of line, therefore an adjustment must be provided for offsetting this side pull.

Referring to Figure 5, the core 68 of the broom has a hollow center 80 into which the hub 81 is secured by the cap screws 81' holding the hub 81 in position. The arbor shaft 69 has an integral flange 69' forming part thereof. A shaft 68' passes through the hub 81 extending into the hollow arbor 69 which accurately centers the core 68 with the arbor 69. The flange 69' of the arbor 69 is bolted to the hub 81 by the cap screws 81''. The tail stock 71 has a hollow chuck 82 which receives the opposite end of the shaft 68' and the chuck 82 is maintained against the end of the shaft by the fixed collar 83 bearing against one of the bearings 72.

When the carriage 73 is brought to the proper position for supporting the brush core 68, the hand wheel 84 is revolved, bringing the set screw 85 down against the top of the rail 20, preventing the movement of the carriage 73. The arbor shaft 69 is revolved by the motor 56 and gear reduction box 87 through the chain 88.

In the applying of bristles to the core 68, the bristle feeding assembly B is moved along the core 68 in the following manner, referring particularly to Figures 3 and 10. A downwardly extending arm 89 is indirectly secured to the transverse bar 41, forming part of the bristle feeding assembly B, as above described. The arm 89 supports a pair of tandem wheels 90 journalled within a wheel supporting frame 91.

The frame 91 is pivotally mounted by its bracket 92 to the lower end of the arm 89 at 93. This permits the tandem wheels 90 to follow the spiral grooves 94 on the periphery of the core 68, as best illustrated in Figure 10. As the wheels 90 follow the groove 94 they will move the bristle feeding assembly B along the core 68 while applying the bristles 67 to the core 68. The tandem wheels 90 can be retracted from the core 68 when mounting the core 68 in place by means of a hand wheel 95 forming part of the brace 96 pivotally connected at 97 to the lower end of the arm 89.

It has been found that when two wheels 90 are operated

in tandem that a smoother feed can be maintained between the core 68 and the bristle feeding assembly B, as sometimes the grooves 94 are deformed, therefore, by providing two wheels 90, one behind the other, a more constant feed is maintained.

The upper end of the arm 89 is pivotally mounted to a transverse threaded rod 98 fixedly secured to the bar 41 by supporting brackets 99. The transverse position of the arm 89 can be varied by the repositioning of jamb nuts 100 upon the threaded shaft 98. The transverse position of the arm 89 determines the alignment of the bristles 67 when entering the grooves 94 of the core 68.

A bristle binding core rope 101 is fastened into one end of the spiral groove 94. The core 68 is then rotated and the bristles are fed into the groove 94 with the rope 101 being tightly pulled into the groove 94 by the rotation of the core 68 binding the bristles 67 therein.

The rope 101 passes around a drum 102 which has a 20 brake band 103 operating on an extension brake drum 104, the tension of the brake band 103 is adjusted by an adjusting screw 105. The tension of the brake band 103 determines the tightness of the winding of the rope 101 within the groove 94 of the core 68. A friction block 25 106 applies a tension on the rope 101 so that the rope 101 will grip the drum 102 in its operation.

The drum 102 and brake assembly are mounted upon a framework 107, mounted to the table 34 by legs 108. The drum 102 and brake assembly is journalled to the 30 cross shaft 109 journalled to the framework 107 on bearing blocks 110. The brake band 103 is in two parts, referring to Figures 13 and 14, pivotally connected on one side of the assembly to a bracket 111 fixedly mounted to the framework 107. The bands 103 are brought together on the opposite sides of the brake assembly by the adjusting screw 105 depending on the amount of resistance to be offered to the movement of the bristle binding rope 101.

Bristle guides 112 are mounted above the bristle feeding assembly B by brackets 113, referring to Figures 3 and 10. Guards 114 are provided along the bristle feeding assembly B to prevent the bristles 67 from entering into the assembly in the operation of the machine W.

As the bristles 67 are wrapped within the grooves 94, 45 they are trimmed to the proper diameter by the trimming unit T. The trimming unit T includes a drum-like housing 115 having a revolving cutter blade 116 operating therein. The blade 116 is mounted on a shaft 117 on a motor 118. The upper edge of the drum 115 is 50 cut away at 119. The ends of the bristles 67 are guided into this cut out portion by the guides 120 where they are trimmed as the core 68 is being revolved in the winding of the bristles 67 to the core 68.

The trimming unit T is supported on the outer ends 55 43 of the rails 38 and 39 by hangers 121. The hangers 121 are fixedly secured to the trimmer T at 122 and extend upwardly and horizontally at 123 passing through a hollow sleeve 124 where they are locked in adjusted position by a set screw 125. This adjustment moves 60 the trimmer T relative to the broom core 68 in order to adjust the same to the various diameter brooms being rewound.

The operation of this broom winding machine W will 65 now be described. The hand wheel 84 of the tail stock carriage 73 is released, permitting the movement of the carriage 73 along the channel base frame 20. The hand wheel 95 is operated to retrack the tandem wheels 90 away from the center line between the arbor shaft 69 and the tail stock 71 a sufficient distance to mount the broom core 68 to the arbor 69 and the chuck 82 of the tail stock 71. The tail stock carriage 73 then is moved towards the core 68 and locked in the position shown in Figure 1 by the hand wheel 84 when the core 68 has 70 been brought into position. Next the bristle feeding as-

sembly B is moved towards the right, as viewing Figure 1, to the beginning of the groove 94 of the core 68. The tandem wheels 90 are then moved towards the core 68 into the groove 94 by the hand wheel 95.

The outer ends 43 of the rails 38 and 39 are adjusted for the proper distance from the inserted broom core 68 to properly apply the bristles 67 to the core 68. This is accomplished by adjusting the hanger rods 47 to either raise or lower the outer ends 43 of the bristle feeding assembly B. The position of the trimmer T is determined, depending upon the outer diameter of the bristles 67 of the broom to be wound by loosening the set screw 125 and moving the horizontal portion 123 of the hangers 121 to the proper position for trimming the broom to be wound.

The end of the rope 101 is secured within the beginning of the groove 94 conventionally. The bristles 67 are placed on the table 34, as shown in Figure 4. The bristles 67 are moved by the fingers 66 on the upper runs of the chains 54 towards the right when viewing Figures 3, 4 and 10, under the rope 101, and as the bristles 67 approach the core 68 they are pulled down into the groove 94 and as they are pulled down they enter between the horizontal fingers 65 of the chains 54, which continue to move them in synchronism with the rotation of the core 68 down into the groove 94, and as they rotate their outer ends enter the cut away portion 119 of the trimming unit T, where the revolving cutter blade 116 trims them to the proper length.

As the bristles 67 are placed on the table and fed over the chains 54, they will continue to feed into the groove 94 of the core 68 and be bound therein by the binding rope 101, and as the core 68 is revolved the groove 94 will move the bristle feeding assembly B towards the left as viewing Figure 1, until the complete winding operation is finished and the core has been completely rebristled.

As the bristles 67 are pulled down between the rails 38 and 39, they are further assisted by the guides 112 in arriving at the proper position for entering the groove 94 of the core 68. The rails or guards 114 prevent the bristles 67 from re-entering the space between the rails 39 after they have been applied to the core 68.

Having thus described the preferred embodiment of the invention, it should be understood that numerous structural modifications and adaptations may be resorted to without departing from the scope of the appended claims.

What is claimed is:

1. A broom winding machine for applying bristles to a broom of the type having a spiral groove extending along the outer surface of a cylindrical core with the bristles fastened therein by a rope secured in the groove; comprising a stationary framework, means on said framework for supporting said core adjacent the rear of said framework for rotary movement, a carriage extending from front to rear through said framework and supported

therein for movement parallel to the axis of said core, said carriage extending transversely of and overlying said core, a pair of conveyor chains on said carriage arranged in spaced apart converging relation generally transverse to the axis of said core, a pair of spaced parallel sprockets having generally horizontal axes mounted on said carriage supporting each of said chains, said conveyor chains sloping upwardly and rearwardly from the front portion of said carriage to the rear portion thereof, a plurality of spaced parallel bristle engaging fingers secured to each of said chains with each of said fingers having a generally horizontal leg and a generally upright leg, opposed fingers on said chains having the generally horizontal legs in substantially aligned inwardly projecting relation and the upright legs in generally parallel relation, and means on said carriage and movable therewith for applying tension to said rope during rotation of said core and guiding said rope along a downwardly and rearwardly sloping path between said conveyor chains from a point above said conveyor chains to said core, said conveyor chains being adapted to support a plurality of bristles extending transversely thereof with said upright legs of said fingers moving said bristles toward said core, said tensioned rope being wound on said core on rotation of said core and engaging said bristles intermediate the opposite ends thereof moving said bristles downwardly into a generally V-shaped form and clamping the bristles centrally in the spiral groove of said core, said bristles disengaging from said upright legs and simultaneously engaging the horizontal legs of said fingers as the bristles are pulled into the generally V-shaped form by said rope.

2. A device as claimed in claim 1 wherein a pair of converging arms are secured to said carriage overlying said conveyor chains for engaging beneath the outer ends of said bristles for cooperating with said rope in applying pressure to and guiding said bristles into the groove in said core.

3. A device as claimed in claim 1 wherein the means applying tension to said rope includes a drum journaled on said carriage about which said rope is trained and means retarding the rotational movement of said drum.

4. A device as claimed in claim 1 wherein means are provided on said carriage for moving said carriage laterally with respect to said core and with said last named means having portions thereof engaging in the spiral groove in said core.
